UNITED STATES PATENT OFFICE.

BAXTER P. HAMILTON, OF BROOKLYN, NEW YORK, ASSIGNOR TO AMERICAN TELEPHONE AND TELEGRAPH COMPANY, A CORPORATION OF NEW YORK.

SELECTIVE CIRCUITS FOR MULTIPLEX SIGNALING.

Application filed September 23, 1919. Serial No. 325,681.

To all whom it may concern:

Be it known that I, BAXTER P. HAMILTON, residing at Brooklyn, in the county of Kings and State of New York, have invented certain Improvements in Selective Circuits for Multiplex Signaling, of which the following is a specification.

This invention relates to multiplex signaling and more particularly to an arrangement of selective circuits for maintaining the channels of a multiplex system electrically separate.

In order to obtain the maximum service from a pair of wires used for telephonic transmission, it is desirable that as many signaling channels as possible be superposed upon the pair of wires, in order to utilize as great a range of the frequency spectrum as possible. If the frequency spectrum be considered to comprise all of the frequencies lying between zero and infinity, it will be seen that the frequencies employed in ordinary telephonic transmission, which may be considered to lie between 200 and 2500 cycles per second, occupy but a relatively small part of the total frequency spectrum, so that it is possible to superpose channels upon the pair of wires, both above and below the telephonic range. The upper limit of frequencies available for superposition of channels above the telephonic range will, of course, be far short of infinity, because of the limitations imposed by the transmission characteristics of the line. In the case of ordinary open wire circuits, it is not ordinarily practicable to transmit frequencies higher than about 30,000 cycles.

In accordance with the present invention it is proposed to utilize the maximum extent of the practicable signaling range, by superposing on the pair of wires, in addition to the ordinary telephone channel an ordinary Morse channel whose frequency is in the neighborhood of about 16 cycles, one or more alternating current telegraph channels having frequencies in the neighborhood of 100 cycles and one or more high frequency carrier channels which may be used for either telegraph or telephone signaling, having frequencies from say 4,000 or 5,000 cycles up to the highest frequency which can be efficiently transmitted. An additional channel for the purpose of transmitting ringing signals can also be superposed on the

same pair of wires, this channel having assigned to it a frequency within the voice range. It is possible to do this by reason of the fact that ringing and talking do not take place simultaneously.

In order to provide proper frequency separation between the several channels superposed upon the same conductor, an arrangement of filters is provided in accordance with this invention, said arrangement comprising a number of separate broad band filters, certain of which may be upper limiting or low pass filters, others of which may be lower limiting or high pass filters, and still other of which may be filters transmitting a band of frequencies whose upper and lower limits lie below infinity and above zero respectively, in the total frequency spectrum. These filter units are so associated with the common transmission path and the several superposed branches and are so designed as to render the several branches mutually exclusive as regards the frequencies of all other branches.

The invention may now be readily understood from the following description when read in connection with the accompanying drawing, Figures 1, 2 and 3 of which constitute circuit diagrams of three different embodiments of the invention.

Referring to Fig. 1, ML designates a telephone transmission line upon which a plurality of signaling channels may be superposed in the manner about to be described. L_1 , L_2 , L_3 , L_4 and L_5 designate a plurality of branches whereby signaling channels may be established over the line. The line L_1 may be used for metallic circuit Morse signaling. The average frequency used for signaling of this character may be in the neighborhood of 16 cycles. The line L_2 may be utilized for transmitting telegraph signals by low frequency alternating currents. The line L_3 may be utilized for impressing ordinary telephonic frequencies upon the line. These frequencies may be assumed to lie between 200 and 2500 cycles. The line L_4 may be used for impressing one or more relatively high frequency carrier signaling channels upon the line. These carrier channels may, of course, be used for the transmission of either telephone or telegraph signals.

In order to provide for frequency separa-

tion between the several branch circuits, a system of filters is provided. These filters are broad band filters of the type described in the U. S. patents of George A. Campbell, Nos. 1,227,113 and 1,227,114, dated May 22, 1917. In accordance with the principles disclosed in the Campbell patents, these filters constitute a network having a plurality of sections, each section including series and shunt impedance elements so proportioned as to transmit bands of frequencies between pre-assigned limits. The filters may be in general of three types, depending upon the location of the band transmitted by the filter with respect to the entire frequency spectrum. The first type is the so-called low pass or upper limiting filter which transmits a band of frequencies lying between zero and any upper limiting frequency greater than zero, but less than infinity. The second type is the so-called high pass or lower limiting filter which transmits a band of frequencies lying between infinity and a lower limit greater than zero. The third type transmits a band lying between a lower limit greater than zero and an upper limit less than infinity. The low pass and high pass filters are sometimes known as ultra and infra filters respectively.

In order to carry out the principles of this invention an ultra or a low pass filter LF_1 is inserted in the line L_1 . Each section of this filter, it will be noted, consists of series inductances, and shunt capacity, these elements being so proportioned as to make the upper limiting frequency transmitted by the filter about 30 cycles. Since this frequency is lower than the lowest frequency transmitted over any of the other branches, L_2 , L_3 , etc., it serves to prevent frequencies from the other channels from producing interference on the line L_1 , while affording a path of low impedance to Morse frequencies transmitted over the line L_1 . In order to prevent these Morse frequencies from reacting in any of the other circuits an infra or high pass filter HF_2 is inserted in the line ML between its junction with the line L_1 and its junction with the next higher line L_2 . The filter HF_2 , it will be noted, comprises a plurality of sections, each section including series capacity and shunt inductances, these elements being so proportioned that the filter will freely transmit frequencies from 80 cycles up to infinity, but will substantially suppress frequencies below 80 cycles. Since the frequencies from the lines L_2 , L_3 , etc., are all above 80 cycles, these frequencies may be transmitted through the filter HF_2 to the line ML , but since the frequency transmitted over the line L_1 is below the lower limiting frequency of the filter HF_2 , the Morse frequencies cannot react on the lines L_2 , L_3 , etc.

An ultra or low pass filter LF_2 is included

in the line L_2 , said filter being so designed as to transmit frequencies from zero to 120 cycles, thus affording a path of low impedance for an alternating telegraph transmission having a frequency of about 100 cycles. This filter serves to prevent higher frequencies from the lines or branches to the left of the line L_2 from reacting on the latter line. In order to prevent the frequencies incoming from the line L_2 from reacting on the higher frequency lines to the left thereof and at the same time readily permit frequencies from such other lines to be transmitted to the main line ML , a high pass filter HF_3 is connected in the main line between its junction with the line L_2 and its junction with the line L_3 . This filter is designed to transmit frequencies from 200 cycles up.

A low pass filter LF_3 is included in the line L_3 , this filter having an upper cut-off at about 2500 cycles, thereby freely transmitting voice frequencies which ordinarily comprise frequencies ranging from 200 to 2500 cycles. The upper cut-off of this filter is lower than the carrier frequencies which will be transmitted from the line L_4 and consequently the carrier frequencies cannot react on the telephone branch. In order to prevent the voice frequencies from reacting in the carrier branch L_4 , a high pass filter HF_4 is inserted in the connection between the main line and the branch L_4 . This filter, in the case illustrated, has a lower cut-off of 4,000 cycles, thereby freely transmitting carrier frequencies from 5,000 cycles up to 100 say 25,000 or 30,000 cycles, these frequencies being the highest frequencies it is practicable to transmit over an ordinary telephone line as now constructed. Obviously if the transmission line is adapted to transmit higher frequencies, additional carrier channels of higher frequency may be employed.

In addition to the channels hereinbefore described, it is usually necessary in connection with the telephone channel L_3 , to provide means for ringing over the main line ML . For this purpose an additional branch L_5 is provided between the filter HF_3 and its junction with the line L_3 . This channel may be used for transmitting ringing frequencies in the neighborhood of 300 cycles. While this frequency lies within the range of ordinary telephonic transmission incoming from the line L_3 , it is possible to use a frequency in this range, by reason of the fact that ringing current will not, in practice, be transmitted to the line while talking, and consequently the channel L_5 will be disconnected during telephonic transmission. This channel is provided with a filter BF , which, it will be observed, is composed of sections having inductance and capacity in series and parallel inductance and capacity in shunt with the line. A filter of this type falls within the third classification herein-

before referred to, that is, it transmits frequencies between an upper limit less than infinity and a lower limit greater than infinity. Since it is only desired to transmit one frequency over the channel L_5 , the inductances and capacities should be so proportioned as to bring the limiting frequencies quite close together upon either side of 300 cycles. With a filter thus constructed, it is obvious that frequencies from channels transmitting frequencies any considerable extent above or below 300 cycles cannot react upon the channel L_5 .

A modified arrangement is shown in Fig. 2. In this form of the invention the main line ML has Morse legs L_1 and L_1' associated therewith, so that each side of the line may be utilized for the transmission of Morse currents. Branches L_2 , L_3 and L_4 are also provided for superposing alternating current telegraph signals, ordinary telephone frequencies and high frequency carrier channels upon the main line ML . The Morse legs L_1 and L_1' are provided with low pass filters LF_1 and F_1' , respectively, for freely transmitting Morse frequencies while suppressing the high frequencies which are transmitted over the branches L_2 , L_3 and L_4 . The branch L_2 , which is to be used for the transmission of frequencies in the neighborhood of 100 cycles, is provided with a band filter BF_2 whose upper and lower limiting frequencies lie closely adjacent on either side of 100 cycles. This filter may be of the general construction of the filter BF of Fig. 1, that is, each section should comprise series inductance and capacity, with parallel inductance and capacity in shunt with the line. This filter will, of course, prevent Morse signals as well as higher telephone and carrier frequencies from reacting on the circuit L_2 .

The telephone line or branch L_3 is also provided with a band filter BF_3 of construction similar to the band filter BF of Fig. 1. The inductance and capacity elements of this filter are so designed as to make its upper and lower cut-off frequencies about 2500 and 200 cycles respectively. This will allow free transmission of telephonic frequencies to the main line ML and will prevent the reaction of the lower telegraph frequencies or the higher carrier frequencies from the other branches. The branch L_4 , which is intended for the transmission of carrier currents to be utilized for either telephone or telegraph signaling, may be equipped with a filter and since there is no necessity for providing against the reaction of higher frequencies in this circuit, it is sufficient to include in the circuit merely a high pass filter HF_4 having a lower cut-off in the neighborhood of 4,000 cycles. This will prevent the lower frequencies from reacting on the branch L_4 and at the same time

will readily permit the passage of the high carrier frequencies from this branch to the main line ML .

It will be noted that in accordance with this arrangement of the invention the use of high pass filters between the junction points of the various branches with the main line, is avoidable, thus reducing the number of filters necessary, as compared with Fig. 1. However, it necessitates the use of a number of the more complex filters of the third type hereinbefore referred to, which have their upper and lower cut-offs below infinity and above zero respectively. Filters of this type are, of course, more expensive than filters employing simple inductances and capacities in their shunt and series branches.

Fig. 3 shows substantially the same arrangement as that of Fig. 2, except that an additional channel is provided for ringing or signaling in connection with the establishment of a telephone connection. The several filters in the branches L_2 , L_3 and L_4 are simply indicated schematically and it will be understood that they are constructed in the same manner as the corresponding filters BF_2 , BF_3 and HF_4 of Fig. 2. In connection with Morse channel L_1 , the low pass filter LF_1 , indicated schematically, will be understood to be similar to the filter LF_1 of Fig. 1, although if grounded Morse legs such as illustrated in Fig. 2 are to be used, it will be understood that separate low pass filters will be divided in each leg, as indicated in Fig. 2.

In order to apply the ringing signal to the telephone line, a branch connection L_5 is bridged across the line L_3 and the ringing signal is applied to this bridge through a transformer and tuned circuit arrangement TF . Band filters BF and BF' are included on each side of the transformer TF , these band filters being of the same type as the filter BF of Fig. 1. The function of these filters is to prevent the reaction of the lower telegraph frequencies and the higher carrier frequencies upon the branch L_5 . Two filters, BF and BF' are provided, simply for purposes of balance. It will, of course, be understood that since ringing signals are not transmitted at the same time that talking is taking place, the branch L_5 may be disconnected when the line L_3 is in talking condition, thereby preventing voice frequencies in the neighborhood of 300 cycles from being diverted into the shunt path through L_5 .

It will be obvious, of course, that the various frequencies hereinbefore referred to and indicated upon the drawing, are merely for purposes of illustration and that in practice other frequencies than those indicated may be used, the essential requirement being merely that the frequencies assigned to the various channels and to the correspond-

ing filters be so chosen as to provide for proper frequency separation between the channels.

It will also be obvious that the general principles herein disclosed may be embodied in many other organizations widely different from those illustrated without departing from the spirit of the invention as defined in the following claims.

10. What is claimed is:

1. In a signaling system a transmission line, a plurality of branches from said line for transmitting a plurality of signaling frequencies superposed upon said line, said branches being connected across the terminals of said line in parallel, in the order of the frequencies assigned to them, so that the branch transmitting the highest frequency will be farthest from the line, a low pass filter in each branch, adapted to transmit frequencies between zero and an upper limit at least as great as the maximum frequency assigned to the branch and less than the lowest frequency to be transmitted over the 20 next highest branch, and high pass filters included in the transmission line between each pair of branches, each high pass filter being arranged to transmit a band of frequencies between infinity and a lower limit 25 which is greater than the frequency assigned to the lower branch and less than the lowest frequency to be transmitted at the higher of the two branches.

2. In a signaling system, a transmission line, a plurality of branches associated therewith, one of said branches being adapted for the transmission of Morse signals, another branch being adapted for the transmission of low frequency alternating current telegraph signals, a third branch being designed for the transmission of voice frequencies and a fourth branch being designed for the transmission of carrier frequencies higher than voice frequencies, upper limiting filters in certain of said branches, the upper limit of the filter in the Morse branch being greater than the highest frequency used in Morse signaling and less than the low frequency alternating telegraph frequency, the 40 upper limit of the filter in the alternating current telegraph branch being higher than the frequency assigned to said branch and lower than the lowest Morse frequency, the upper limit of the filter in the telephone branch being at least as high as the highest voice frequency to be transmitted and lower than the lowest carrier frequency of the fourth branch, and high pass filters between each pair of branches, the lower limit of each 50 high pass filter lying between the highest frequency assigned to the branch immediately below it and the lowest frequency assigned to the branch immediately above.

3. In a selective system, a plurality of 60 pairs of filters, each pair of filters comprising

ing a high-pass filter and a low-pass filter, a circuit for impressing currents of different frequencies on said system, a plurality of branch circuits for receiving selected ranges of said impressed frequencies, the 70 frequencies transmitted to each branch being the frequencies that are transmitted selectively by the joint action of the filters of at least one of said pairs of filters, and transmission also taking place successively 75 through certain filters of different pairs.

4. In a selective system, a plurality of pairs of filters, each pair of filters comprising a high-pass filter and a low-pass filter, a circuit for impressing currents of different frequencies on said system, branch circuits for receiving selected ranges of the impressed frequencies, the frequencies transmitted to each branch circuit being the frequencies that are transmitted selectively by 80 the filters of at least one of said pairs of filters, and the frequencies transmitted to certain of said branches being the frequencies that are transmitted by one pair of said filters and at least another of said 85 filters in common.

5. A selective system comprising a line having a plurality of filters in series in said line and a succession of branched circuits for said line, one branch being connected to 95 the output terminals of each of said filters, each said filter of the series freely transmitting currents of all the frequencies common to all the branched circuits except those preceding it in the series, and a filter for each 100 branched circuit freely transmitting for said branched circuit currents of frequencies which are transmitted in common by all said filters preceding it in the series, said filters substantially extinguishing currents 105 of the frequencies which they do not freely transmit.

6. A pair of filters connected in series having a transmission range of frequencies common to both filters, one of said filters substantially extinguishing currents of all frequencies lower than said range of frequencies, the other of said filters substantially extinguishing currents of all frequencies higher than said range of frequencies, another pair of filters similarly associated with each other, one of which is connected in series with the corresponding filter of the first pair and a branch circuit connected to each of the other filters.

7. Pairs of filters, the filters of each pair being connected in series and having a transmission range of frequencies common to both filters, one of said filters of each pair substantially extinguishing currents of all frequencies lower than said range of frequencies, the other of said filters of said pair substantially extinguishing currents of all frequencies higher than said range of frequencies, the corresponding filters of the 130

successive pairs being connected in series and a branch circuit connected to each of the other filters, each of said corresponding filters that are connected in series extinguishing a portion of the currents that are freely transmitted by the preceding filter of the series.

8. A series of filters having successively different sharply defined cutoff frequencies and each substantially extinguishing currents of all frequencies lying to the same side of its respective cutoff frequency but freely transmitting currents of all frequencies lying to the opposite side of said cutoff frequency, a branch circuit connected to the output terminals of each of said series filters containing a filter having a sharply defined cutoff frequency and substantially extinguishing currents of all frequencies lying to one side of said cutoff frequency but freely transmitting a range of the frequencies that are transmitted by the filter to which it is connected.

9. The combination of filters each of which freely transmits currents of all frequencies higher than a predetermined cutoff frequency and substantially extinguishes currents of all frequencies lower than said cutoff frequency, other filters each of which freely transmits currents of all frequencies lower than a predetermined cutoff frequency and substantially extinguishes currents of all frequencies higher than its said cutoff frequency, said filters being associated in pairs consisting of one filter of each kind in series, having a transmission frequency range in common, all the filters of one kind being connected in series and a branch circuit connected to each filter of the other kind.

10. The combination of filters each of which freely transmits currents of all frequencies higher than a predetermined cutoff frequency and substantially extinguishes currents of all frequencies lower than said cutoff frequency, other filters each of which freely transmits currents of all frequencies lower than a predetermined cutoff frequency and substantially extinguishes currents of all frequencies higher than its said cutoff frequency, said filters being associated by pairs consisting of one filter of each kind in series, having a transmission frequency range in common, all the filters of one kind being connected in series and a branch circuit connected to each filter of the other kind, the cutoff frequency of each filter of said one kind in series being within the transmission range of all of the filters which precede it in the series.

11. A selective circuit comprising filters of two kinds, each filter having a sharply defined cutoff frequency, certain of said filters comprising reactance elements which substantially extinguish currents of all frequencies

greater than their respective cutoff frequencies, while freely transmitting currents of all other frequencies, and others of said filters comprising reactance elements which substantially extinguish currents of all frequencies lower than their respective cutoff frequency while freely transmitting currents of all other frequencies, a plurality of filters of one kind connected in series relation, filters of the other kind connected to the output terminals of the respective filters of said one kind, the transmission range of each filter of said other kind overlapping that of the filter to which it is connected.

12. A selective circuit comprising filters of two kinds, each filter having a sharply defined cutoff frequency, certain of said filters comprising reactance elements which substantially extinguish currents of all frequencies greater than their respective cutoff frequencies, while freely transmitting currents of all other frequencies, and others of said filters comprising reactance elements which substantially extinguish currents of all frequencies lower than their respective cutoff frequency while freely transmitting currents of all other frequencies, a plurality of filters of one kind connected in series relation, filters of the other kind connected to the output terminals of the respective filters of said one kind, the transmission range of each filter of said other kind overlapping that of the filter to which it is connected, and the transmission range of each filter of one kind being included in the transmission range of each of the filters which precede it in the series.

13. In a system of filters comprising filters which transmit substantially only frequencies lower than an upper limiting frequency and other filters which transmit substantially only frequencies higher than a lower limiting frequency, a plurality of filters of one of said kinds connected in series and a branch circuit connected between each two of said filters, each of said branch circuits containing a filter of the other of said kinds having a transmission range in common with those filters that are in series and to one side of the respective branch circuit.

14. A plurality of pairs of filters one filter of each pair being a low-pass filter and the other a high-pass filter, a circuit common to all of said filters for conveying currents of different frequencies successively through certain filters of different pairs, and a branch circuit individual to each of said pairs of filters for conveying currents of only the frequencies that are transmitted by the filters of said pair.

In testimony whereof, I have signed my name to this specification this 20th day of September 1919.

BAXTER P. HAMILTON.
